UNITED STATES PATENT OFFICE.

ROY S. WINGERT, OF NEWTON, MASSACHUSETTS, ASSIGNOR TO MARTIN MANUFACTURING COMPANY, OF NEWTON, MASSACHUSETTS, A CORPORATION OF MASSACHUSETTS.

DESIGN FOR LACE FABRIC.

No. 39,530.

Specification for Design.

Patented Sept. 8, 1908.

Application filed June 16, 1908. Serial No. 438,861. Term of patent 3½ years.

To all whom it may concern:

Be it known that I, ROY S. WINGERT, a citizen of the United States, residing at Newton, in the county of Middlesex and State of Massachusetts, have invented a new, original, and ornamental Design for Lace Fabrics, of which the following is a specification, reference being had to the accompanying drawing, forming a part thereof.

The figure is a plan view of a piece of lace fabric showing my new design.

I claim:

The ornamental design for a lace fabric, as shown.

ROY S. WINGERT.
